STYLUS BRACE FOR STEPBACK
MECHANISMS

Lincoln Thompson, Cheshire, and Robert L. Stone,
Hamden, Conn., assignors to The Soundscriber
Corporation, New Haven, Conn., a corporation
of Connecticut

Original application April 17, 1941, Serial No.
388,956. Divided and this application May 3,
1943, Serial No. 485,480

4 Claims. (Cl. 274—14)

This invention relates to improvements in mechanisms for sound reproduction and more particularly to a stylus brace for phonograph stepback mechanism for a transcribing machine employing disk records.

This application is a division of our prior application, Serial No. 388,956, filed April 17, 1941, entitled "Stepback mechanism for phonograph transcribers," patented on June 29, 1943, Number 2,323,257.

The present invention is especially designed for dictating machines employing disk records of the type disclosed in Patent No. 2,200,866, issued May 14, 1940, to Lincoln Thompson, on an application filed December 15, 1938, Ser. No. 245,944, entitled "Disk dictating machine," reissued September 22, 1942, No. 22,183, and constitutes an improvement over the step-back mechanism disclosed in our prior Patent No. 2,240,321, dated April 29, 1941, entitled "Transcribing machine."

In transcribing machines of the above nature, it is often desirable for the typist to play over a portion of the recorded dictation, and the present invention has for its principal object, the provision of an improved form of solenoid-operated "step-back" mechanism for back-spacing the pick-up needle a short distance over the record without raising the needle from or stopping the rotation of the turntable.

A further object is to provide means to brace the reproducing needle while the step-back action is taking place.

A still further object of this invention is to provide an improved form of step-back mechanism of the above nature which will be relatively inexpensive to manufacture, simple in construction, compact, ornamental in appearance, and very efficient and durable in use.

With these and other objects in view, which will appear as the description proceeds, there has been illustrated in the accompanying drawings one form in which the invention may be conveniently embodied in practice.

In the drawings:

Figure 1 is a perspective view of a transcribing machine embodying the features and principles of this invention.

Figure 2 is a top plan view on an enlarged scale of the improved step-back mechanism shown in cooperating relation with the reproducing pick-up carrying member.

Figure 3 is a side view of the same, looking in the direction of arrow 3 of Figure 2.

Figure 4 is a front view of a portion of the

step-back mechanism, looking in the direction of arrow 4 in Figure 2.

Figure 5 is an enlarged fragmentary top view of a portion of the step-back mechanism illustrating by full and dotted lines three different operating positions of the same.

Figure 6 is a fragmentary side view partly in section of the sound reproducing unit and its carrying arm.

10 Figure 7 is an end view of the same.

Figure 8 is a schematic view of the invention including a diagram of the electrical circuits and control mechanism.

Referring now to the drawings wherein like reference numerals designate like parts throughout the several views, the numeral 10 denotes a casing over which a disk record supporting turntable 11 is adapted to rotate. The turntable 11 is arranged to be driven by an electric motor 12 (see Figure 8).

Provision is made of an arm 13, (see Figures 1, 2, 6, and 7), carrying a sound reproducing "pick-up" unit 14, which is hingedly secured thereto by a flat leaf spring 15, and also connected thereto by a coiled counter-balancing spring 16—said arm 13 being pivoted at 17 to the casing top 18 so as to swing over a thin disk record 19 carried by the turntable 11. The pick-up unit 14 carries a reproducing needle 20 which rides in the sound track previously formed on the surface of the record 19 by a recording machine (not shown) and vibrates said pick-up unit 14, which is connected by conductors 21 and 22 to the input terminals of a vacuum tube amplifier 23 (see Figure 8). The output terminals of said amplifier 23 lead through conductors 24 and 25, to a loudspeaker or other sound reproducer, not shown.

As herein shown, the back-spacing or step-back means for the pick-up needle includes a flat frame plate 26 (see Figures 2, 3, 4, and 5), which is adapted to be adjustably secured upon the casing 10, or to any other suitable stationary part of the transcriber, as by a screw 27 extending 45 through an elongated inclined slot 28 formed in said frame 26.

Mounted on the frame 26 is an electromagnet generally indicated by the numeral 29, having a U-shaped core 30, the upper leg 31 of which is 50 surrounded by a wire coil 32. The magnet 29 is pivotally secured to the frame member 26 by a vertical screw pin 33 which passes through the upper leg 31 and lower leg 34 of the core 30 at a point adjacent the curved base of said core. The coil 32 is adapted to be energized by elec-

55

tric current from a pair of wires L1 and L2 through conductors 35 and 36, under the control of a switch 37, preferably hand or foot-operated, and located in circuit with said coil.

Provision is also made of a movable iron armature 38 of light weight which is pivoted to the end of the arm 31 as by a pin 39. The armature 38 is loosely mounted in a slot 40 provided in the free end of the leg 31, whereby said armature will be supported against lateral movement, and will be carried by the electromagnetic core 30 when the latter swings on its screw pivot pin 33. The armature 38 extends a short distance upwardly beyond the arm 31, and carries on its outer face, adjacent its upper end, a pointed lug or knife-edge 41 which is adapted to engage with a side bar 48 on the pick-up arm to be described later.

In order to limit the swinging movement of the armature 38 in a direction away from the leg 34, provision is made of a stop finger 42 bent upwardly from the frame 26 into position to be engaged by the lower end of said armature 38, when the core 30 is not magnetized. A coiled tension spring 43 is connected at one end to a fixed angular post 44 preferably secured, at one end, to an upstanding ear 45 on the frame 26 by soldering, or brazing. The other end of the spring 43 is attached to the armature 38 at a point intermediate the upper and lower legs 31 and 34 of the core 30. The spring 43 thus serves to constantly urge the lower end of the armature 38 against the stop finger 42, and also acts to urge the electromagnetic core 30 toward the upturned frame ear 45 and into contact with a horizontal adjustable stop screw 46 which is screw-threaded through said ear 45 and is locked thereto by a lock nut 47.

The side bar 48 of the pick-up arm 13 is secured to said arm adjacent the rear end thereof as by rivets and said side arm extends into the path of the upper end of the armature 38 so that whenever the electromagnetic core 30 is magnetized by current passing through the coil 32, the knife-edge 41 will engage the curved edge 49 on the end of the side bar 48. The edge 49 is curved preferably on an arc struck from the center of the pivot 17 of the pick-up arm 13, so that when said pick-up arm 13 swings over the record 19, the curved edge 49 will at all times be equidistant from the knife-edge 41.

In use, when the magnet 29 is energized, the armature or clapper 38, due mainly to its low inertia, will respond quickly to the attraction of the leg 34 of the core 30. The knife-edge 41 will thus engage the arcuate end of the side bar 48 with a "biting" action. Shortly, thereafter, due to its higher inertia, the magnet core 30 will be caused to swing backwardly due to a stationary iron post 50 which extends upwardly from the side of the frame plate 26 opposite to the side on which the stop screw 46 is disposed. The force due to the attraction between the legs 31 and 34 of the core 30 and the post 50 will cause the side bar 48 to back-space the pick-up arm any desired number of grooves according to the adjustment of the stop screw 46, it being understood that the needle will not be lifted from the record during this action.

The above described combined action of the armature 38 and the magnet core 30 is illustrated in Figure 5 wherein the initial position of the side bar 48 is shown in full lines, and its back-spaced position in dotted lines. It will be understood that upon energization of the coil

32 to magnetize the core member 30, the leg 34 of the magnet core 30 will attract the armature 38, which being relatively light in weight and low in inertia, will be quickly swung about the pivot pin 39, causing the sharp point 51 of the knife-edge 41 to engage the curved end 49 of the thin side bar 48, as indicated at A in Figure 5. The relatively heavy core 30 will be slightly delayed in responding to the magnetic field but will swing on its pivot screw 33 toward and against the armature post 50, as indicated at B in Figure 5, due to the magnetic attraction between the legs 31 and 34 of the core 30 and said post 50. The bar 48 will thus be caused to move from the full line position to the dotted line position as shown in Figure 5. It will be clear from the above explanation that the knife-edge 41 will move in a somewhat angular path, first engaging the edge of the side bar 48, and then moving laterally with said bar through the desired amount of back-spacing.

After the switch 37 is opened the armature 38 will be released from the magnetic attraction of the core 30 and will swing quickly due to the action of the spring 43 back into contact with the lug 42. The core 30 will then swing more sluggishly back to its original full line position, shown in Figure 5.

In order to brace and support the needle 20 against being bent when the pick-up unit 14 is stepped-back by the mechanism above described, provision is made of an angle block 52 secured to the underside of said pick-up unit, just behind the needle 20 (see Figure 7). The block 52 has a vertical arm 53 which is disposed closely adjacent to the reproducing needle 20, but not so close as to interfere with the normal vibrations thereof.

The pick-up unit used for the transcriber mechanism herein disclosed, should preferably be of the type disclosed in Patent No. 2,213,936, issued September 3, 1940 to Lincoln Thompson, wherein the needle movement is extremely flexible, the brace 52 being essential in order that the movements of the reproducer arm 13 should be transmitted to the needle 20 without excessive backlash, and yet permitting said needle to execute its normal vibrations without striking said brace 52. A further advantage of the use of the brace 52 is that the depending leg 53 will positively jar and vibrate the needle at each actuation so that it will never come to rest in the flat land between two adjacent grooves.

Operation

In operation, whenever the typist listening to the loudspeaker reproduction of the record 19 in response to the pick-up unit 14 wishes to replay any desired portion of the record, it will only be necessary when this portion has been played to manually close the switch 37, which will be placed in a readily accessible position. The closing of the switch 37 will energize the coil 32, and thus magnetize the core 30, whereupon the light armature 38 will be quickly moved into engagement with the side bar 48. The heavy magnet core 30 will be more slowly swung about its pivot 33 and the combined action of the armature and core will cause the pick-up needle 20 to slide back over the record the predetermined number of grooves. If a greater number of grooves are to be replayed, the switch may be actuated two or more times in succession.

While there has been disclosed in this specification one form in which the invention may be

embodied, it is to be understood that this form is shown for the purpose of illustration only, and that the invention is not to be limited to the specific disclosure, but may be modified and embodied in various other forms without departing from its spirit. In short, the invention includes all the modifications and embodiments coming within the scope of the following claims.

Having thus fully described the invention, what is claimed as new and for which it is desired to secure Letters Patent, is:

1. In an electrical phonograph reproducer, a pickup, means to secure a reproducing record-engaging needle having considerable flexibility to said pickup, and a vertical brace plate depending from said pickup in close proximity to said needle and located closely adjacent to the record surface to protect said needle from excessive backlash movements of said pickup and yet permitting it to execute its normal vibrations without striking said brace plate.

2. In an electrical phonograph reproducer, a pickup head, means to secure a laterally-flexible record-engaging needle to said head, means to step-back said needle a predetermined number of grooves to permit that portion of said record to be transcribed, and an angular block secured to said head and having a vertical brace section located in close proximity to said needle to protect the latter from excessive backlash movements of said head and yet permit said needle to execute its normal vibrations without striking

said brace section, said vertical brace extending to a point close to the record surface.

3. In an electrical phonograph reproducer, a pickup head, means to secure a laterally-flexible record-engaging needle to said head, means to step-back said needle a predetermined number of grooves to permit that portion of said record to be transcribed, and an angular block secured to said head and having a vertical brace section located slightly in advance of said needle in the direction of its travel to protect the latter from excessive backlash movements of said head and yet permit said needle to execute its normal vibrations without striking said brace section, said vertical brace extending to a point close to the record surface.

4. In a phonograph transcriber, a rotating turntable, a disk record carried by said turntable, a pickup head mounted to swing across said record, means to secure a depending record-engaging needle having considerable lateral flexibility to said head, means to step-back said needle a predetermined number of grooves to permit that portion of said record to be transcribed, a depending brace carried by said head and located slightly in advance of said needle in the direction of its travel whereby said brace will positively jar said needle at each actuation of said step-back means so that said needle will never come to rest on the flat land between two adjacent grooves.

LINCOLN THOMPSON.

ROBERT L. STONE.
